UNITED STATES PATENT OFFICE

160,856

BEDSPREAD COVER OR SIMILAR ARTICLE
FOR ELECTRICALLY HEATED BLANKETS

Joseph Goodstein, New York, N. Y.

Application April 25, 1950, Serial No. 9,458

Term of patent 7 years

(Cl. D92—2)

To all whom it may concern:

Be it known that I, Joseph Goodstein, a citizen of the United States of America, residing in New York city, county of New York, and State of New York, have invented a new, original, and ornamental Design for a Bedspread Cover or Similar Article for Electrically Heated Blankets, of which the following is a specification, reference being had to the accompanying drawing, forming part thereof, wherein.

Figure 1 is a front elevational view of a bedspread cover for electrically heated blankets, showing my new design.

Figure 2 is a rear elevational view thereof, drawn on a smaller scale, showing the ruffle portion in partly detached position.

I claim:

The ornamental design for a bedspread cover

or similar article for electrically heated blankets, substantially as shown.

JOSEPH GOODSTEIN.
